TERMINAL LUG AND MOUNTING BLOCK

Theodore J. Obszarny, Chicago, Ill., assignor to Guardian Electric Manufacturing Co., Chicago, Ill., a corporation of Illinois

Application April 9, 1951, Serial No. 219,923

3 Claims. (Cl. 339—220)

The present invention relates to terminal lugs and terminal blocks on which such lugs are mounted, which are, by way of example and not limitation, especially suitable for use in conjunction with hermetically sealed, electromagnetic relays.

Hermetically sealed relays as heretofore produced, include a relay component or device, completely enclosed in a sealed chamber of a metallic housing or case, and having conductor wires connected to the various sets of pole contacts of the relay and to the terminals for supplying of electrical energy to the coil of the relay. Such wires extend in sealed relation through a bulkhead or partition wall in the case and are connected to terminal lugs carried on a terminal block or mounting panel. The projecting ends or terminal portions of the conductor wires, which extend into the sealed chamber and are connected to the various sets of pole contacts and terminals associated with the coil of the relay, are extended through the wall of the terminal block, and also extend into openings formed in the terminal lugs.

The terminal lugs heretofore employed each have a depending tubular sleeve extending through the wall of the block with the free end of the sleeve spun outwardly to provide a hollow rivet type of connection of the lug to the block. The interior of the sleeve is threaded for the reception of a terminal screw for securement thereto of a terminal clip on the end of a conductor wire of an electrical circuit to be controlled by the relay.

More particularly the present invention is directed to terminal lugs and terminal blocks of the type adapted for handling of relatively heavy electrical currents, such as in the range of 100 amperes. For such use, the terminal lugs necessarily are formed of sheet metal stampings of rather heavy gauge metal. By reason of the connection of the lugs to the terminal block in the manner above referred to, it frequently happens that the lug is caused to rotate incident to tightening or loosening of the terminal screw which secures the terminal clip of a conductor wire to the lug. It has been found that frequently when installing a relay in the "field," in the process of connecting of conductor wires, of electrical circuits to be controlled, to the terminal lugs, by means of the terminal screws, the force employed in tightening or loosening such screws tends to place the conductor wires, extending from the relay proper within the sealed chamber, under a shearing stress, and frequently results in shearing of such wires, and thus rendering the total hermetically sealed relay device non-useful, and necessitating re-working thereof and re-installation of new conductor wires from the pole contacts or the terminals of the relay coil.

One of the objects of the present invention is to provide a novel and improved form of terminal lug and terminal block especially adapted for handling of heavy electrical currents, and which is constructed and arranged so as to eliminate the above mentioned objectionable conditions.

Another object is to provide a novel heavy duty terminal lug and terminal block construction which limits ro-

2

tative movement of the lug when it is attached to the block.

A further object is to provide a novel heavy duty terminal lug and terminal block construction provided with interengaging features, serving to limit rotative movement of the lug on the block for precluding possible shearing of the conductor wire which extends through the block and is soldered to the lug.

Still another object is to provide an improved heavy duty terminal lug and terminal block which is relatively simple in construction, durable in use and capable of being economically manufactured.

Other objects and advantages of this invention will be apparent from the following description taken in connection with the accompanying drawing, in which:

Figure 1 is a face view of a relay assembly provided with terminal lugs and a terminal block embodying the present invention;

Figure 2 is a view in side elevation of the relay assembly, with certain portions broken away to show details of construction;

Figure 3 is an enlarged sectional view through the terminal block, taken substantially as indicated at line 3—3 on Figure 1;

Figure 4 is an enlarged, fragmentary face view of a portion of the terminal block showing one of the terminal lugs mounted in position thereon;

Figure 5 is a sectional view taken at line 5—5 on Figure 4; and

Figure 6 is an enlarged, perspective view of the terminal lug embodying the present invention.

In Figures 1 and 2 of the drawing, there is disclosed a conventional hermetically sealed type of relay wherein the relay proper is indicated generally at 10 in dotted outline, totally enclosed in a cup-shaped housing or case 11, formed of sheet metal. Adjacent the open end of the case, there is formed an inwardly projecting bead or shoulder 12, against which is seated a bulkhead 14 in the nature of a partition wall, the peripheral edges of which are sealed to the inner wall of the case, as by solder, as indicated at 15. It is to be understood that the bulkhead is provided with a suitable fitting, not shown, for conveniently evacuating the closed chamber of the case, below the bulkhead, and for permitting the introduction therein, if desired, of a suitable inert, non-inflammable gas, after which the fitting is sealed off so as to insure proper functioning of the relay proper under a wide range of temperature and humidity conditions.

The various sets of pole contacts of the relay as well as the terminals associated with the coil of the relay are connected by conductor wires, as indicated at 17, which extend through the bulkhead 14, and which are sealed with respect thereto by conventional glass bead sealing devices, indicated generally at 18.

The outer end of the case 11 is closed by a terminal block 20, formed of suitable electrical insulating material, the underside of which is formed with a depending peripheral flange 21, for snug fitted engagement in the open end of the case. The free end portions 17a of the conductor wires 17 extend through the insulating terminal block 20 and are connected to suitable terminal lugs, as will be hereinafter described.

For each terminal in the nature of a pole contact, and each terminal connection for the coil of the relay proper, there are provided corresponding terminal lugs on the outer face of the terminal block 20, and to which lugs may be attached, the ends of the respective conductor wires of the electrical circuits to be controlled by the relay, and the circuits for supplying electrical energy to the coil. The outer face of the terminal block is formed with a plurality of outwardly extending, substantially

parallel, spaced apart ribs 22, defining terminal mounting areas.

The construction as represented in the drawings is for a relay having two sets of pole contacts for which there is provided, on the outer face of the terminal blocks, four terminal lugs indicated at 25. Because the construction herein disclosed is for heavy duty use—that is, the circuits being controlled utilize heavy current, in the range of 100 amperes, the terminal lugs 25 are formed of relatively heavy gauge sheet metal, and are formed as stampings. The terminal lugs are of generally rectangular shape, having depending from one side thereof, a tubular sleeve 26, and at one end, there is formed a U-shaped notch 27. The terminal mounting areas of the terminal block for each terminal lug is formed with two apertures 28 and 29, as clearly seen in Figure 4 of the drawing, the large aperture 28 accommodating the sleeve 26 of the terminal lug therein, and the sleeve being of such length that it projects beyond the inner surface of the main wall of the block, and said end is spun or rolled outwardly in the nature of a hollow rivet for firmly securing the lug in place on the block. The aperture 29 accommodates therethrough the terminal portion 17a of a conductor wire which extends into the U-shaped notch 27 of the terminal lug. It is to be understood that any excess length of such conductor wires are severed so that the end of said wire projects substantially flush with the upper surface of the terminal lug. The terminal ends 17a of the conductor wire are then firmly secured to the respective terminal lugs by solder, as indicated at 30, and which connection serves as the medium for securing the total terminal block and terminal lug assembly to the open end of the case 11.

As may be seen in the drawing, the terminal lugs 25 are so dimensioned and located as to provide a surface extending in relatively close relation to an adjacent rib 22 of the terminal block, and attention is directed to the fact that the construction as represented in Figures 3-6, inclusive, of the drawing, represents the parts at approximately twice actual size, and, therefore, it will be appreciated that one edge of the terminal lug is caused to be positioned extremely close to the adjacent rib 22 on the terminal block, and thus any tendency for rotative movement of the terminal lug is immediately limited by abutment of the lug against the adjacent rib. It is to be noted that the opening or aperture 29 through which the terminal portion 17a of the conductor wire from the interior of the casing 11 extends, is of a size slightly in excess of the diameter of the wire 17a, so as to permit a limited amount of movement of the terminal portion 17a of the conductor wire with the lug 25, before abutting against a rib 22, without imposing any shearing strains upon said portion of the conductor wire, incident to the rotative movement of the terminal lug.

The inner wall of the sleeve 26 of the terminal lug is threaded, and is adapted for the reception of a terminal mounting screw 32 for securing a terminal clip 33 carried on the end of a conductor wire 34, which, in turn, is connected in and constitutes a part of the electrical circuits being controlled by the relay 10.

It will be apparent that in tightening or loosening the terminal screws 32 in connection with securing or removing the terminal clips 33 with respect to the terminal lugs 25, there is often a tendency to impart rotative movement to the terminal lugs 25, and except for the blocking arrangement provided by the ribs 22 on the terminal block, there is a possibility that such rotative movement of the terminal lugs would effect shearing of the end of the terminal portion 17a of the conductor wire 17, which would, as above indicated, render the total relay assembly defective by reason of the severance of a conductor wire attached to a terminal lug and would necessitate removal of the total relay device and re-working the same by introduction of a new conductor wire 17, which may in some instances cause serious delay, as for

example in aircraft construction, and necessitate the expenditure of substantial time and added cost in the matter of re-working of the relay device.

Although the terminal lugs 25, as shown, are provided with relatively straight sides, obviously, if desired, they might be formed with projecting nibs at opposite ends for cooperative engagement with an adjacent rib of the terminal block to serve as an abutment for limiting rotative movement of the terminal lug. The ribs 22 also serve to permit close spacing of the terminal lugs and serves as an electrical barrier to preclude possible short circuiting across terminal lugs.

At the lower portion of the terminal block, there is provided a pair of terminal lugs, as indicated at 36 which may be understood to be the same as the terminal lugs constituting the invention disclosed in my co-pending application, Serial No. 219,922, filed April 9, 1951, now Patent No. 2,701,870 dated February 8, 1955. The terminal lugs 36 may be understood to be connected to conductor wires extending into the case 11, the opposite ends of which are connected to terminals for the coil of the relay. It is possible to use lugs of the type designated at 36 for controlling the coil of the relay because of it being possible to utilize considerably lighter current, as compared to current which may be employed in the circuits being controlled through the sets of pole contacts of the relay proper.

Although I have herein shown and described a preferred embodiment of my invention, manifestly it is capable of modification and rearrangement of parts without departing from the spirit and scope thereof. I do not, therefore, wish to be understood as limiting this invention to the precise form herein disclosed, except as I may be so limited by the appended claims.

I claim as my invention:

1. A terminal mounting block formed of electrical insulating material, having a terminal mounting face provided with one or more outwardly extending ribs defining separate terminal mounting areas, and a plurality of terminal lugs connected to said block in said areas, and each having a tubular sleeve seated in an aperture formed in said area, with the free end of the sleeve extending beyond the undersurface of the block and spun outwardly for firmly securing said lug to the block, said lugs each being formed with an opening, spaced from the sleeve, and registering with an aperture in the block for the reception in the respective aperture and opening of the terminal portion of a conductor wire disposed at the side of said block opposite to said terminal areas, said lugs each having portions disposed in close proximity to said ribs for opposing rotative movement of said lugs.

2. A terminal mounting block formed of electrical insulating material, having a terminal mounting face provided with one or more outwardly extending ribs defining separate terminal mounting areas, and a plurality of terminal lugs connected to said block in said areas, and each having a tubular sleeve seated in an aperture formed in said area, with the free end of the sleeve extending beyond the undersurface of the block and spun outwardly for firmly securing said lug to the block, and lugs each being formed with a peripheral, U-shaped notch, spaced from said sleeve, and registering with an aperture in the block for the reception in the respective aperture and notch of the terminal portion of a conductor wire disposed at the side of said block opposite to said terminal areas, said lugs each having portions disposed in close proximity to said ribs for opposing rotative movement of said lugs.

3. A terminal mounting block formed of electrical insulating material, having a terminal mounting face provided with one or more outwardly extending ribs defining separate terminal mounting areas, and a plurality of terminal lugs connected to said block in said areas, and each having a tubular sleeve seated in an aperture formed in said area, with the free end of the sleeve extending be-

yond the undersurface of the block and spun outwardly for firmly securing said lug to the block, said lugs each being formed with an opening, spaced from the sleeve, and registering with an aperture in the block for the reception in the respective aperture and opening of the terminal portion of a conductor wire disposed at the side of said block opposite to said terminal areas, said aperture being substantially larger than the cross-section of the wire to permit limited relative rotative movement between said block and said terminal lugs and wire, said 10 lugs each having portions disposed in close proximity to said ribs for opposing rotative movement of said lugs and precluding imposition of shearing strains on the wire in the zone between said lugs and terminal block.
